(57) **CLAIM**

I claim the ornamental design for a wearable jewelry item, as shown and described.

DESCRIPTION

FIG. 1 is a perspective view of the wearable jewelry item forming a part of the present design;

FIG. 2 is a front view forming a part of the present design; and,

FIG. 3 is an isometric right side view forming a part of the present design, a corresponding left side being a mirror image thereof.

It being understood that the broken lines are for illustrative purposes only.
